UNITED STATES PATENT OFFICE

159,425

CHANGE-MAKER

Edward F. Leese, Everett, Wash.

Application June 24, 1949, Serial No. 3,499

Term of patent 14 years

(Cl. D52—4)

To all whom it may concern:

Be it known that I, Edward F. Leese, a citizen of the United States of America, residing at Everett, in the county of Snohomish and State of Washington, have invented a new, original, and ornamental Design for a Change-Maker, of which the following is a specification, reference being had to the accompanying drawing, forming part thereof.

Figure 1 is an end elevation of a change-maker, showing my new design;

Figure 2 is a front elevation thereof; and

Figure 3 is a plan view thereof.

The essential features of my design reside in the portion shown in full lines.

I claim:

The ornamental design for a change-maker, substantially as shown and described.

EDWARD F. LEESE.
